UNITED STATES PATENT OFFICE.

WALLER P. TINSLEY, OF FORT WORTH, TEXAS, ASSIGNOR OF ONE-HALF TO JNO. A. WISHERD, OF FORT WORTH, TEXAS.

GAS-GENERATOR.

1,130,861.

Specification of Letters Patent.

Patented Mar. 9, 1915.

Application filed March 1, 1913, Serial No. 751,496. Renewed July 23, 1914. Serial No. 852,781.

To all whom it may concern:

Be it known that I, WALLER P. TINSLEY, a citizen of the United States, residing at Fort Worth, in the county of Tarrant and 5 State of Texas, have invented certain new and useful Improvements in Gas-Generators, of which the following is a specification.

My invention relates to gas generators, and particularly for generating hydrocar- 10 bon gases of whatever kinds and elements employed, and the object is to provide ample and efficient means for feeding gas making elements into the fillings or contents located in the generators and to distribute uni- 15 formly to all parts of a generator the elements fed into the generator and to provide efficient means for operating the feeding devices and to provide agitating devices working in combination with the feeding 20 devices for agitating the fumes within the generator.

Other objects and advantages will be fully explained in the following description and the invention will be more particularly 25 pointed out in the claims.

Reference is had to the accompanying drawings which form a part of this application.

Figure 1 is a vertical section of the feed- 30 ing devices within the generator and a sectional view of a generator with a front view of the mechanism for operating the feeding devices. Fig. 2, is an enlarged side elevation of the distributing cup. Fig. 3 is an enlarged bottom view of one of the distributing pipes. Fig. 4 is a vertical section 35 of the box for the feed distributing shaft. Fig. 5 is a horizontal section of the feed operating shaft, taken on the line A—B of Fig. 4, the part of the stuffing box 29 below 40 the line being omitted to show the collar 32.

Similar characters of reference are used to indicate the same parts throughout the several views.

45 A portion of a generator 21 is shown in section with a top 20. A feed cup 22 is carried by a vertical shaft 4. A bearing flange 19 is fixedly attached to the top of the generator and a pipe 2 forming a neck 50 is screwed into the flange 19. A reducer T-pipe 1 is screwed down on the neck 2 and a boss is formed on the upper side of the reducer T-pipe 1. A feed pipe 3 is projected upwardly within the neck 2 and 55 screwed through the boss 37 to receive a T-

pipe 5. A feed pipe 17 is mounted in the T-pipe 1 by a bushing 18. The T-pipe 5 is a four-way T-pipe and a pipe 10 is mounted in the connection 14 by means of an elbow 11 and pipe 12. The pipe 10 forms a 60 support for the bearing 9 in which the shaft 8 is journaled. A bevel gear 7 is rigidly mounted on the shaft 8 by a hub 15 and set screw 16. The T-pipe 5 has a connection 14 for a pipe to be connected to a supply source 65 of material to be fed to the generator. A collar 32 is rigidly mounted on the shaft 4 and a bearing 6 has a reduced portion screwed into the T-pipe 5. A gland is provided for the shaft 4 and this gland consists of the box 29 screwed into the bearing block 6, a cover 31, and a cap 30 screwed on a reduced portion of the box 29. A bevel gear 7' is rigidly mounted on the upper end 70 of the shaft 4 by means of a hub 15 and set screw 16.

Distributing pipes 23 are connected to and communicate with the feed cup 22. These pipes have perforations 26 in the lower sides and baffle rings 24 are mounted 80 on the pipes below the perforations 26 to cause the material fed to the generator to fall and to prevent the material from clinging to and running down the under sides of the pipes. The pipes 23 are closed at the 85 outer ends by caps 25. At the inner ends the pipes 23 are screwed into bosses 27 and open into the cup 22. Attention is called to the arrangement of the rings 24 and the perforations 26. The rings and perforations 90 on one pipe are arranged in staggered relation to the rings and perforations on the other pipe so that instead of four circles of feeding material falling, there will be eight 95 circles with the devices shown. The pipes 23 carry wings 36 mounted thereon to serve as mixers for fumes which may arise above the gas making material within the generator. The joint 33 between the cup 22 and the pipe 3 is not a sealed joint, the cup 100 turning freely about the pipe 3.

The generator is to be charged with whatever material that may be desired for making gas. The liquid elements are to be fed through the pipe 3, coming in the opening 14. Compressed air is fed through the pipe 17 into the generator. The shaft 8 may be driven by any suitable power for rotating the shaft 4 and the distributing arms 23, and agitating wings 36. 110

2
Various changes may be made in the feeding devices without departing from my invention.

What I claim, is,—

- 5 1. Feeding devices for gas generators comprising a liquid container suspended within a generator, perforated distributing arms connected to and communicating with and carried by said container, baffle rings 10 mounted on said arms, the baffle rings on each arm being placed at different distances from the container relative to the baffle rings on every other arm and means for rotating said container.
- 15 2. In a generator provided with a perforated top, a hollow neck connected in the perforation in said top, a connection with said neck for feeding compressed air into the generator, a pipe projected through said 20 neck for feeding liquid elements to the gen-

erator, a shaft projected through said pipe into the generator, a liquid container carried by said shaft and loosely connected with said pipe, perforated distributing pipes carried by said container, a stuffing gland for 25 said shaft, and means for driving said shaft.

3. Feeding devices for gas generators comprising a liquid container suspended within a generator, perforated distributing arms communicating with and carried by said 30 container, agitating wings carried by said arms, and means for rotating said container.

In testimony whereof, I set my hand in the presence of two witnesses, this 26th day of February, 1913.

WALLER P. TINSLEY.
